UNITED STATES PATENT OFFICE

MICHAEL GEORGE BACHMANN, OF ASHLAND, OHIO

INGOT TYPE-METAL MOLD

Application filed April 25, 1929. Serial No. 357,998.

This invention relates to improvements in ingot molds or casters and has for its object the provision of such mold composed of two angularly shaped sections, a body section 5 and a door section. These sections are so related to each other that they form a rectangular cavity, two sides of which are formed by each section of the mold. In a caster or mold of this kind the ingot does not stick in the mold after the door section 10 is open. No jolting or prying are necessary to loosen the ingot from the mold. The mold is of the same thickness throughout the entire length of the cavity thereby doing away with stuck ingots in metal feeder housing.

By this means whenever the door section is opened from the body section the ingot can be easily removed on account of the angular shape of the body and the door.

It is also a purpose of this invention to provide a water-cooled body so that the ingot, after being cast, is immediately cooled and upon opening the door the ingot will separate from the body and can be removed 25 easily.

It is also an object of this invention to provide an ingot mold composed of few parts that are easily assembled and replaced and easily operated for the purposes for which 30 they are intended.

For purposes of illustration there is shown in the accompanying drawings a preferred embodiment of this invention.

Referring to the drawings:

Figure 1 is a side view of the mold in position for receiving the molten metal for the formation of an ingot.

Figure 2 is a similar view with the door open.

Figure 3 is a top plan view of the mold as shown in Figure 1.

Figure 4 is a top plan view of the mold as shown in Figure 2.

Figure 5 is a perspective view of the top 45 of the mold with the door closed.

Figure 6 is a perspective view of the top of the mold with the door only slightly open.

Figure 7 is a view similar to Figure 1 but taken on an angle of forty-five degrees to 50 that shown in Figure 1.

Figure 8 is a view similar to Figure 7 showing the mold with the door open.

This apparatus is composed essentially of two sections, an angularly shaped body section indicated by the numeral 1, which has 55 in one corner thereof a ratchet 2, and a door section 7.

In this body section there is a water space, indicated by the numeral 3, which has an inlet orifice 4 and an inlet pipe 4^a. There is 60 leading from this water space an outlet orifice 5 which leads into an outlet pipe 5^a. The other section of the apparatus constitutes a door and is indicated by the numeral 7.

For the purpose of providing a seat for 65 this door there are angular seat spaces 6 formed in the body section so that there may be formed between the two a close fitting engagement.

On the door there is a plurality of hinge 70 members 8. There may be any number of these members, though three are shown in the drawings. Corresponding hinge members are also found on the body and are indicated by the numeral 10. The door members 75 of the hinges are fastened to the door by means of screws 9, while the cooperating members of the hinges are attached to the body by means of screws 11. The points where the hinges are pivoted to each other 80 are indicated by the numeral 12.

For the purpose of manipulating the door there is attached thereto a handle 13. There is also arranged on the door a suitable number of lugs 14, to be engaged by cooperating 85 members on the body for the purpose of locking the door to the body. The cooperating members on the body are the clamp levers 15 pivoted to the body at the points indicated by the numeral 16.

The parts of the levers immediately engaging the lugs 14 are the hook members 17. For the purpose of engaging the lugs 14 upon the release of the hook member 17 there are formed on the clamp levers lips 18. 95 These lips cooperate with the hook members 17 to form a seat for the lugs 14. These lips are so positioned that when the clamp levers 15 are thrown to disengage the hooks 17 from the lugs 14, the lips 18 will engage 100

the lugs 14 and partially open the door. After the door is thus partially opened it may be completely opened by the handle 13.

The outer ends of the clamping levers have attached thereto a connecting link 19. This link is pivotally attached to the clamping levers by means of bolts 20. The purpose of this link is to connect the clamping levers so that on the operation of one lever, all the clamping levers will be operated so that each one will engage a lug 14 or be disengaged therefrom by the same operation. For the purpose of operating the clamping levers there is attached thereto, at the pivot point between one of the clamping levers and the link, a handle 21.

The lower part of the mold is closed so that when the body and the door are fastened, as shown in Figures 1 and 3, the metal may be poured into the upper end, which is open, and will be retained in the cavity formed therein since the lower part is closed. When the metal has been poured and the ingot cast, the levers 15 are released from the lugs and the door is partially opened because of the lips 18 engaging the lugs 14.

For the complete opening of the door the handle 13 is grasped and the door is swung entirely open. When the door is thus opened the ingot is exposed on two sides, leaving only two sides in engagement with the body of the mold. And since these two sides are at right angles to each other it is easy to remove the ingot from the body. In fact, the ingot is in a condition to drop therefrom as soon as the door is completely opened.

In a mold constructed of two angular parts cooperating with each other to form a rectangular cavity, the ingots cast therein do not stick to the mold but are readily released therefrom when the door is open, and no prying or jolting are necessary to get the ingot loose from the mold because an ingot cast in a mold of this kind has the same thickness throughout its whole length.

I desire to comprehend within my invention such modifications as may be clearly embraced within my claims and the scope of my invention.

Having thus fully described my invention, what I claim is new and desire to secure by Letters Patent, is:

1. In an ingot mold, an angular shaped body member, and a door attached to said body member and forming therewith an ingot cavity, said body member being provided with water space having an inlet and outlet.

2. In an ingot mold, an angular shaped body member, a door attached to said body member and forming therewith an ingot cavity, said body member being provided with water space having an inlet and an outlet, and means for locking the door to the body member.

3. In an ingot mold, an angular-shaped

body member, a door attached to said body member and forming therewith an ingot cavity, and means for locking the door to the body member.

4. In an ingot mold, an angular-shaped body member, an angular-shaped door attached to said body member and forming therewith an ingot cavity, and means for locking the door to the body member.

5. In an ingot mold, an angular-shaped body member, an angular-shaped door attached to said body member and forming therewith an ingot cavity, said body member being provided with a water space, and means for locking the door to the body member.

6. In an ingot mold, an angular-shaped body member having door seats thereon, a door attached to said body member and adapted to engage said seats, and means to lock said door in engagement with said seats to form with the body member an ingot cavity.

7. In an ingot mold, an angular-shaped body member having door seats thereon and a water space therein, a door attached to said body member and adapted to engage said seats, and means to lock said door in engagement with said seats to form with the body member an ingot cavity.

8. In an ingot mold, a body member, a door for said body member forming therewith an ingot cavity, lugs on said door and clamp means on said body member, said clamp means including lug-engaging locking means, and means on release of said locking means to engage the lugs to partially remove the door from the body member.

9. In an ingot mold, a body member, a door for said body member forming therewith an ingot cavity, lugs on said door, clamp levers on said body, hook means on said clamp levers to engage said lugs to hold the door to the body member, and means on said clamp levers adapted as the hook means are released from said lugs to engage said lugs to partially remove the door from the body member.

10. In an ingot mold, an angular-shaped body member, an angular-shaped door for said body member forming therewith an ingot cavity, lugs on said door, and means on said body member to engage said lugs to lock the door to the body member and adapted on release of the lugs to further engage the lugs to partially remove the door from the body member.

11. In an ingot mold, an angular-shaped body member, an angular-shaped door for said body member forming therewith an ingot cavity, lugs on said door, clamp levers on said body member, hook means on said clamp levers to engage said lugs to lock the door to the body member, and means on said clamp levers to engage said lugs on the release of the hook means therefrom to partially remove the door from the body member.

tially remove the door from the body member.

12. In an ingot mold, an angular-shaped body member having a water space therein, an angular-shaped door for said body member forming therewith an ingot cavity, lugs on said door, and means on said body member to engage said lugs to lock the door to the body member and adapted on release of said lugs to further engage said lugs to partially remove the door from the body member.

13. In an ingot mold, an angular-shaped body member having a water space therein, an angular-shaped door for said body member forming therewith an ingot cavity, lugs on said door, clamp levers on said body member, hook means on said clamp levers to engage said lugs to lock the door to the body member, and means on said clamp levers to engage said lugs on the release of the hook means therefrom to partially remove the door from the body member.

14. In an ingot mold, a body member, a door attached to said body member forming therewith an ingot cavity, lugs on said door, clamp levers on said body member, hook means on said clamp levers to engage said lugs to lock the door to the body member, and a common operating means for said clamp lever whereby the hook means are engaged with the lugs or disengaged therefrom.

15. In an ingot mold, a body member, a door for said body member forming therewith an ingot cavity, lugs on said door, clamp levers pivoted to said body, hook means on one end of said clamp levers to engage said lugs to hold the door to the body member, means on said clamp levers adapted as the hook means are released from said lugs to engage said lugs to partially remove the door from the body member, and a link connecting the other ends of said clamp levers whereby all the levers are operated in unison.

45 16. In an ingot mold, an angular-shaped body member, an angular-shaped door for said body member forming therewith an ingot cavity, a ratchet located in one corner of said angular-shaped body member, lock means on said door, coengaging means on said body member, and common operating means for said coengaging means.

55 17. In an ingot mold, an angular-shaped body member having a water space on each side thereof, an angular-shaped door attached to said body member and forming therewith an ingot cavity, a ratchet located in the corner of said body member and adjacent the water space therein, lock means on said door, a cooperating lock means on said body member, and a common means for causing the engagement and disengagement of the cooperating means and the lock means.

60 18. In an ingot mold, an angular-shaped body member having a water space therein

on both sides thereof, a door attached to said body member forming therewith an ingot cavity, a downwardly inclined ratchet formation located in the corner of said body member adjacent the water space therein, 70 means on the door forming part of cooperating locking means, and a plurality of levers on the body member cooperating with the locking means on the door to hold the door locked to the body means when in one 75 position and when removed from that position to partially open the door.

In testimony whereof, I affix my signature.

MICHAEL G. BACHMANN.
